CLAIM

The ornamental design for a random number selector game, as shown and described.

DESCRIPTION

FIG. 1 is a front, left side and top isometric view of the random number selector game embodying my new design; FIG. 2 is a top plan view thereof;

FIG. 3 is a left side elevational view thereof;

FIG. 4 is a front elevational view thereof;

FIG. 5 is a right side elevational view thereof;

FIG. 6 is a rear elevational view thereof; and,

FIG. 7 is a bottom plan view thereof.

The broken line showing of the balls in FIG. 1 is for illustrative purposes only and forms no part of the claimed design.
